UNITED STATES PATENT OFFICE

150,079

DESIGN FOR A STEAK DICING MACHINE

John Lovse, Detroit, Mich.

Application August 9, 1946, Serial No. 132,377

Term of patent 3½ years

(Cl. D11—1)

To all whom it may concern:

Be it known that I, John Lovse, a citizen of the United States, residing at Detroit, in the county of Wayne and State of Michigan, have invented a new, original, and ornamental Design for a Steak Dicing Machine, of which the following is a specification, reference being had to the accompanying drawing, forming part thereof.

In the drawing

Fig. 1 is a frontal perspective view of a steak dicing machine, showing my new design;

Figure 2 is a rear perspective view of the same;

Figure 3 is a front elevation thereof in a partially closed position;

Figure 4 is a rear elevation thereof;

Figure 5 is a side elevation thereof in a partially closed position; and

Figure 6 is a plan view of the same.

I claim:

The ornamental design for a steak dicing machine, as shown.

JOHN LOVSE.
